UNITED STATES PATENT OFFICE.

CARL HOFFMANN, OF NEW YORK, N. Y.

IMPROVEMENT IN GAS-BURNERS.

Specification forming part of Letters Patent No. **157,602**, dated December 8, 1874; application filed March 28, 1873.

To all whom it may concern:

Be it known that I, CARL HOFFMANN, of the city, county, and State of New York, have invented certain new and useful Improvements in Gas-Burners, of which the following is a specification:

This invention relates to that class of gas-burners known as check gas-burners, in which a cap, tube, or thimble having one or more discharging-orifices at its top is made to fit on an ordinary gas-burner, so as to form a gas expansion-chamber between the eduction-orifice of said burner and that of the cap or thimble. My improvement consists in combining, with the gas expansion-chamber formed between the eduction-orifices of the burner and the cap, a secondary expansion-chamber formed beneath and around the tip of the burner, so as to obtain a steady flame with a changing pressure of the gas.

In the drawings, Figure 1 represents a vertical central section of my burner. Fig. 2 is a side view of the same. Fig. 3 is a vertical central section of a modification thereof; Fig. 4, a side view of the same.

Similar letters indicate like parts in all the figures.

In the drawing, the letter A designates a common burner, which is furnished with a tip, a. With this burner is combined a cap, B, which contains a burner-tip, b, so as to form a gas expansion-chamber, c, between the

orifices of the tips a and b. Beneath and around the sides of the tip a is formed a secondary gas-chamber, d, so that when the pressure of the gas is suddenly changed the gas, on reaching the burner A, will be enabled to expand to a certain degree before it passes up through the tip a, and before it reaches the main expansion-chamber c, and thereby the flame is relieved from all influence of any change in the pressure of the gas, and a steady flame is insured. The cap B shown in Figs. 1 and 2 is provided with an external screw-thread, e, for the purpose of attaching thereto the holder of a lamp-shade or of a chimney. The cap B shown in Figs. 3 and 4 is plain and slightly tapering on its outer surface, so that the ring of a shade-holder can be slipped over it.

What I claim is—

In a check gas-burner constructed with two tips, the combination of a secondary gas expansion-chamber, d, formed around and beneath the tip a, with the main expansion-chamber c, formed between the tip b of the cap B and the tip a of the burner A, all constructed and operated substantially as shown and described.

CARL HOFFMANN.
